UNITED STATES PATENT OFFICE.

CLINT B. SNIDER, OF INDEPENDENCE, KANSAS.

PISTON-RING EXPANDER.

Application filed October 30, 1923. Serial No. 671,695.

To all whom it may concern:

Be it known that I, CLINT B. SNIDER, a citizen of the United States of America, residing at Independence, in the county of 5 Montgomery and State of Kansas, have invented certain new and useful Improvements in Piston-Ring Expanders, of which the following is a specification.

This invention relates to piston ring expanders of the type referred to in the application of Clint B. Snider, filed April 14, 10 1923, Serial No. 632,052 wherein the ring expander devices are capable of being associated with any standard type of piston 15 without in any manner altering the original construction or design thereof, the device disclosed in this application embodying improvements in the art with particular reference to the application above identified.

In piston ring expanders of the type disclosed herein, tubular members extending across the piston inwardly of the hollow head thereof with the ends terminating at 25 the bases of the grooves that receive the resilient piston rings, openings being bored in the piston wall in line with the grooves to accommodate the mounting of the ends of the tubular members. The primary object of the invention is to provide a rigid 30 mounting for the ends of the tubular members to eliminate vibration thereof during use of the piston that is accomplished by outwardly flaring the opening receiving the 35 ends of the tubular members with an outward swaging of the ends of the tubular members to form a substantially interlocking connection between the tubular members and the walls of the piston.

40 A further object of the invention is to provide a bracing strap for the tubular members intermediate the ends thereof, the attaching means for the bracing strap being adjustable to compensate for wear and insure the rigid mounting of the tubular members at all times.

With the above and other objects in view as the nature of the invention is better understood, the same consists of the novel form, 50 combination and arrangement of parts hereinafter more fully described, shown in the accompanying drawing and claimed.

55 In the drawing, wherein like reference characters designate corresponding parts throughout the several views,

Figure 1 is a side elevational view, partly

shown in section of a standard type of piston equipped with the piston ring expanders and the special mounting devices therefor,

60 Figure 2 is a bottom plan view of the piston showing the tubular guide for the ring expanding plunger rod and the centrally positioned bracing straps therefor.

Figure 3 is a side elevational view taken 65 at a different angle from the showing in Fig. 1 illustrating the adjustable screw stud mounting for the ends of the bracing strap,

70 Figure 4 is a detail sectional view showing the outwardly flared opening in the side wall of the piston with the initial position of the tubular guide member for the piston ring expander plunger rod, and

75 Figure 5 is a detail sectional view, similar to Fig. 4 showing the outer end of the tubular guide member swaged outwardly for locking engagement with the flared opening in the wall of the piston.

80 The preferred embodiment of the invention as illustrated in the accompanying drawing includes a piston 1 of a standard type of construction having the usual oppositely positioned internal bearings 2 for mounting upon the upper end of a piston with annular grooves 3 formed in the peripheral wall of the piston for the reception of resilient split piston rings 4.

85 As shown in detail in Fig. 4, the bottom wall 3 of the piston ring grooves 3 is provided with a plurality of spaced outwardly flared openings 5 extending completely 90 through the side walls of the piston. A plurality of tubular guide members 6 are disposed interiorly of the piston 1 and have the ends thereof extending into the outwardly flared openings 5, the upper sides of the intersecting portions of the tubular guide members 6 contacting the lower edge of the rib 7 depending from the head 1a of the piston. It is to be understood that any number 95 of the tubular guide members 6 may be employed and the same are rigidly supported in the piston by outwardly swaging the outer ends thereof as at 5a into binding engagement with the walls of the outwardly flared opening 5 thereby forming a substantially 100 interlocking connection between the tubular guide members and the side walls of the piston to support the guide members in a rigid condition to be so held against all vibratory movements thereof. The ring expander devices, each includes a plunger rod

8 slidable in the outer end of each tubular guide member and carrying upon the outer end thereof an arcuate plunger head 9 disposed in the inner side of the annular piston ring groove 3 and in engagement with the inner face of the ring 4, the plunger rods 8 being normally forced outwardly by coil springs 10 housed within the tubular guide members inwardly of said plunger rods as shown in Fig. 1.

To brace the tubular guide members 6 intermediate their ends, a strap 11 is positioned adjacent the lower sides of the tubular guide members in engagement therewith and screw studs 12 passing through opposite ends of the strap 11 are threaded into the head 1^a of the piston, tightening of the screws 12 causing the strap 11 to hold the tubular guide members into a substantially binding engagement with the depending cross rib 7 thereby insuring a rigid mounting of the tubular guide members at points thereof intermediate the ends.

It is believed that the construction and operation of the device will be fully understood from the above detail description, and while there is herein shown and described the preferred embodiment of the present invention, it is nevertheless to be understood that minor changes may be made therein without departing from the spirit and scope of the invention as claimed.

What is claimed as new is:—

1. In a piston ring expander, the combination with a piston having annular grooves 35

therein for the reception of expansible piston rings and having openings in the bottom walls of the ring receiving grooves, of tubular guide members extending transversely of the piston and seated at their ends 40 in the openings, a strap adjustably connected to the head of the piston and bracing the tubular guide members intermediate their ends and tensioned plunger expanders for the piston ring slidable in the outer ends of 45 the guides in engagement with the ring.

2. In a piston ring expander, the combination with a piston having annular grooves 50

therein for the reception of expansible piston

55

walls of the ring receiving grooves, of tubu-

lar guide members extending transversely of

the piston and seated at their ends in the

openings, a strap adjustably connected to

the head of the piston and bracing the tubu-

lar guide members intermediate their ends,

55

tensioned plunger expanders for the piston

ring slidable in the outer ends of the guides

in engagement with the ring, and an internal

60

transverse rib depending from the head of

the piston engaged by the upper sides of the

tubular guide members for bracing and

spacing the guide members from the head of

the piston.

65

In testimony whereof I affix my signa-

ture.

CLINT B. SNIDER.
